GUARD WHEEL

Application filed December 24, 1930. Serial No. 504,532.

This invention relates to improvements in guard wheels for casters and similar devices.

One of the principal objects of the invention is to provide improved means for preserving and maintaining such a guard wheel in a sanitary condition whereby the collection of disease germs thereon is kept to a minimum, and whereby those that do collect are easily removed and the guard wheel cleansed and disinfected.

Another object of the invention is to provide an improved guard wheel free from pockets that will catch and retain dust and germ deposits, that is easily cleansed, that is freely rotatable, that will have a tendency to deflect dust and germ deposits, that is inconspicuous, and that is preservative of the surfaces with which it comes in contact.

Another object of the invention is to provide an improved guard wheel of these characteristics that is economical of construction and durable as to wear and service.

Other objects of the invention are to provide an improved yielding rimmed guard wheel in which the rim tire may be easily removed and replaced to overcome wear and deterioration without replacing the whole wheel and to provide a light but strong and serviceable guard wheel that is cheap to make and which will have a long life of service.

Other objects and advantages of the invention will become apparent from the following description taken in conjunction with the accompanying drawing. It is apparent that changes can be made in the details of construction and arrangement of parts without departing from the spirit of the invention as expressed in the accompanying claims. We, therefore, do not wish to be limited to the exact details shown and described as the preferred form only has been given by way of illustration.

Referring to the drawing:

Fig. I is a side elevation showing a caster embodying the invention;

Fig. II is a front elevation of Fig. I;

Fig. III is a top view of the guard wheel; and

Fig. IV is a cross section on line IV—IV
50 of Fig. III.

Guard wheels on casters and similar devices have gone into quite extensive use where it is desired to protect walls or other articles from being marred by contact with the caster. They are particularly useful and in much demand in hospitals for beds, operating tables and the like. In the past they have been made with a well or depression on the top surface in order to lighten the construction while preserving the wide contacting face of the wheel. These wells were natural collectors of dust and germs which were held trapped therein. These wells were also difficult to clean. They were a violation of the sanitary rules of well run hospitals and a source of much complaint. It is therefore one of the prime objects of the invention to provide an improved guard wheel that is not only free from these defects but will in addition tend to shed and deflect the greater part of such collections.

It is clear that the entire construction of the prior art guard wheels will have to be discarded and the wheel re-designed on entirely new lines and of different materials to reach the results that we have set forth.

Referring to the drawing wherein similar reference characters denote corresponding parts throughout:

Our guard wheel comprises a center portion 1, preferably of hard rubber, composition, bakelite, fiber or similar substance that is both relatively hard and relatively light. The central portion 1 has the central bearing opening 2 therethrough. The outer periphery of the central portion 1 has the tapered surfaces or faces 3 and 4 forming an inverted V shaped edge. Around the periphery of the central portion 1 is secured the tire 5, preferably of soft, pliant rubber having its inner surface shaped to fit the tapered edge of the central portion. The top surface 6 which extends over the central portion 1 and the tire portion 5 is a continuous plane surface sloping downwardly from adjacent the opening 2 to the extreme edges of the tire. The underside 7 may be made parallel with the top surface, 6, though not necessarily so, and the surface 7 adjacent the opening 2 is extended to form a bear-

ing boss 8 to support the wheel in place on its axle or pintle.

In Figs. I and II the guard wheel is shown mounted in place on the stem 9 of a caster comprising the caster wheel 10 having the 5 axle 11 engaging the sides of the caster fork 12 swivelled on the caster stem 9 by means of the ball bearing 13. The caster stem 9 is riveted or otherwise secured at 14 to the fork member 12. The ball bearing 13 is centered 10 on the stem 9 above the fork member. Above the ball bearing is the bearing support or boss 15 engaging the boss 8 on the surface 7 of the guard wheel. Through the opening 2 of the guard wheel extends the bushing 16 which projects slightly above the surface 6 of the guard wheel. On top of the bushing is the washer 17 giving a slight clearance for the top surface of the guard wheel hence allowing it free, unbound, rotative 15 movement on the bushing 16. Above the washer 17 is the caster sleeve 18 into which the stem 9 is fitted and held in place by the 20 spring 19.

25 In operation the soft pliable rubber face 5 of the guard wheel will engage the contacting wall or article and will rotate on the bushing 16 to give a rolling contact instead of an unyielding gouging contact. With 30 the structure shown the caster can be used either with or without the guard wheel as the bushing 16 or a bearing surface of the same diameter on the stem 9 forming a shoulder at the top of the bushing will support 35 the washer 17 and the sleeve 18 if the guard wheel is removed, so that the one caster may be used either way.

It will be noted that the top surface 6 of 40 the guard wheel is smooth and continuous and inclined downwardly so that dust or other collections are not trapped or held and that the same may be easily cleaned and disinfected. The guard wheel is of solid and 45 light construction and so arranged that the soft pliable tire 5 may be snapped in place or removed. Wear and deterioration from age is easily taken care of by simply removing the old tire 5 and snapping a new one over 50 the edge of the central portion 1, which may be retained and does not have to be replaced.

The tire 5, may be either endless, or it may be a strip with its ends connected or otherwise secured together. If desired the tire 5 may be cemented to the inner portion 1. If 55 it is the tire may be removed by cutting through the cross section of the tire, loosening an end and then stripping it off. This procedure will not injure the inner portion 1.

From the foregoing description it will be 60 seen that we have provided exceedingly simple, efficient and economical means for obtaining all the advantages of the invention.

Having described our invention we claim:

65 1. In a device of the character described for use with a caster bracket and caster stem

a guard wheel for rotatable mounting on the stem, said wheel having a relatively hard non-metallic central portion with a central bearing opening to fit on the stem and a projecting bearing boss surrounding the opening on the lower face of said central portion, and a relatively soft non-metallic annular rim portion surrounding said central portion, the upper surface of the central portion and rim being a continuous convex curved 70 surface and the lower surface thereof being a continuous concave curved surface except for the said projecting bearing boss.

2. In a device of the character described for use with a caster bracket and a caster stem 80 a guard wheel for rotatable mounting on the stem, said wheel having a relatively hard non-metallic central portion with a central bearing opening to fit around the stem and a relatively soft non-metallic annular rim portion surrounding said central portion, the upper surface of said central portion and said rim portion being a continuous convex 85 curved surface from the opening to the rim.

3. In a device of the character described for use with a caster bracket and a caster stem guard wheel for rotatable mounting on the stem, said wheel having a relatively hard non-metallic central portion with a central bearing opening to fit around the stem and a relatively soft non-metallic annular rim portion surrounding said central portion, the joining faces of the rim and central portion being substantially V shaped and the upper 95 surface of said rim and central portion being a continuous convex curved surface from the 100 opening to the rim.
